(57) CLAIM

The ornamental design for an anchor for floating decoy, as shown and described.

DESCRIPTION

FIG. 1 is a perspective view of the anchor for floating decoy; FIG. 2 is a right side view of the invention, the left side view being a mirror image; FIG. 3 is a front elevation view of the invention, the rear elevation view being a mirror image; FIG. 4 is a top plan view of the invention; FIG. 5 is a bottom plan view of the invention; and, FIG. 6 is a perspective view of the invention in use attached to a floating decoy. The broken lines in FIGS. 1-3 and 6 are for purposes of illustration only and form no part of the claimed design.
